BALANCING DEVICE

Swan F. Anderson, Rockford, Ill., assignor of one-half to Ralph F. Anderson, Rockford, Ill.

Application January 17, 1952, Serial No. 266,987

4 Claims. (Cl. 51—169)

1

This invention relates to a method and an apparatus by which wheels such as grinding wheels, polishing wheels, buffing wheels and the like, hereinafter referred collectively as "abrasive wheels," are brought into balance so as to rotate with a minimum of transaxial movement during use.

Wheels of the character referred to above commonly are rotated at high speeds, and as manufactured and sold are usually not well enough balanced for best performance. It has therefore been common practice for the user to balance the wheel when placed on the arbor in order to produce smooth and substantially vibrationless operation. This has largely been a trial and error procedure as distinguished from a definite sequence of steps by which the point of balance is directly and unerringly approached. Furthermore, even though a wheel had been balanced on the arbor, its removal and subsequent replacement on the arbor have necessitated a repetition of the balancing operation.

Among the important objects of the invention is the provision of means for balancing an abrasive wheel such that the wheel, when its condition of balance is once determined, may be removed and replaced on the arbor and the wheel unerringly brought to balanced condition without the necessity for a rebalancing operation.

Another object of the invention is the provision of balancing means adapted to replace the conventional side flange of an abrasive wheel and arranged to be held in assembled relation with the wheel by means of the usual clamping nut carried on the arbor.

A further object of the invention is the provision of a method of balancing abrasive wheels wherein the time required for effecting balance is reduced to a minimum and the usual trial and error method eliminated.

Other objects and advantages will be apparent from the following description and the accompanying drawings, in which:

Figure 1 is a perspective view of a grinder stand showing the invention as incorporated with a grinding wheel;

Figs. 2, 3, 4 and 5 are elevational views illustrating steps of balancing a grinding wheel in accordance with the invention;

Fig. 6 is a transverse section through the balancing attachment; and

Fig. 7 is a fragmentary section on the line 7—7 of Fig. 1.

Figure 1 of the drawings shows the preferred embodiment of the invention as combined with a conventional grinding wheel indicated generally

2

by the numeral 8 carried on an arbor 9 driven from a motor 11 forming part of a conventional grinding stand 12. Obviously, the specific form of the mechanism for driving the wheel is not of importance in connection with the invention.

The balancing attachment comprises in this embodiment two plates indicated generally by the numerals 13 and 14 each having a central opening for the reception of a thimble 15 which serves to maintain the two plates in assembled relationship. The thimble is in the form of a tubular member passing through the central openings of the plates and having a flange 16 at one end adapted to bear against the outer face of the plate 14, as best shown in Figs. 6 and 7. The opening in the thimble 15 is of such size as to be snugly received on the arbor 9 with the plates 13 and 14 carried thereon in the manner shown in Fig. 7 so that when the arbor nut 18 is tightened against the shoulder 16, the plate 13 is pressed against the outer side of the wheel. Normally a spacer plate 19 is interposed on the arbor between the inner side of the wheel and a collar or other stop 21 carried on the arbor. In this manner when the nut 18 is tightened, the wheel is gripped between the spacer plate 19 and the plates 13 and 14.

As best shown in Figs. 6 and 7 the plate 13 of the present embodiment is provided with a central frusto-conical portion 22 and a peripheral coplanar rim 23 so that when the parts are brought to the position shown in Fig. 7 the peripheral rim 23 will seat against the side of the wheel and the frusto-conical portion will be spaced from the wheel in the manner shown, thus providing a certain amount of resiliency as between the nut 18 and the wheel, and providing a stable support against the wheel in an area at some distance from the axis of the arbor. In this instance the plate 14 is of smaller dimensions than the plate 13 so that its perimeter terminates substantially at the inner edge of the portion 23 (though this, of course, is not essential), and this plate likewise has a frusto-conical shape. The plates 13 and 14 are in dynamic balance with respect to the axis of the arbor and the axis of the central openings of the plates except for a small portion of each, which in this instance is provided by an opening 24 in the plate 13 and an opening 25 in the plate 14. These openings are such as to remove or omit identical amounts of metal from the two plates at equal distances from the axis of the central openings so that when the two openings are placed on the same diameter of the wheel, they do not affect the

balance of the assembly. In the present instance these are formed by drilling equal sized holes through the plates 13 and 14 which are formed of sheet metal of equal thickness, the center lines of these holes being at equal distances from the axis of the central openings.

It is convenient, though not essential, to make the plates 13 and 14 of circular configuration so that when the plate 14 is placed in face to face relation to the plate 13 as shown in the drawings, the plate 13 will have a marginal exposed area which in this instance is substantially the width of the portion 23. The plate 13 is provided with indicia as indicated at 26 in the form of graduations arranged along its perimeter in the exposed area, which graduations extend through 90° about the axis of the central opening. Conveniently these graduations are numbered or lettered progressively from a point disposed at 90° with respect to a diameter passing through the axis and through the center of the opening 24 and extending to the radius on the opposite side of the axis from the opening 24. Likewise the plate 14 has indicia indicated at 27 extending progressively from a radius disposed at 90° with respect to a diameter passing through the axis and through the center of the opening 25, which graduations extend through 90° to the diameter on the opposite side of the axis from the opening 25. In this instance the graduations are numbered zero to ten, as will be observed from the drawings, progressing from the 90° radii in opposite directions in inverse order.

The method of balancing the wheel is illustrated in Figs. 1-5 in which the numeral 31 indicates a conventional balancing stand or balancing way, such as are well known in the art. The first step illustrated in Fig. 2, comprises introducing a spindle 32 into the opening of the wheel which is shown in this instance as a conventional grinding wheel. The spindle and wheel are then placed on the balancing stand and allowed to come to rest in the usual manner. Thereupon a mark such as shown at 33 is placed vertically on the side of the wheel in any convenient permanent manner for indicating the radius defining the center of the unbalanced segment of the wheel. Thereafter the plates 13 and 14 constituting the balancing attachment are placed on the spindle 32 as shown in Figs. 3 and 5 with the two zeros of the graduations in alignment. This should not disturb the balancing of the wheel but should allow it to rest in the position shown in Fig. 3. If desired or more convenient the balancing attachment can be assembled with the wheel in the first instance. The operator can at this point usually estimate roughly the degree of unbalance based on the rate at which the wheel swings on the stand and can, therefore, estimate the amount of adjustment between the two plates, which may be required to effect balance. He thereupon adjusts the plates by rotating them with respect to each other and with respect to the wheel to bring like numbers of the graduations 26 and 27 into alignment with the line 33. The operator again tries the matter of balance on the wheel, and if insufficient or excessive again adjusts the plates. In all instances like numbers on the two plates are maintained in alignment with the line 33. It will be observed that these adjustments bring the openings 24 and 25 downward as will be apparent from Fig. 4 so as to lighten the lower

or heavy side of the assembly. When the assembly is thus brought into balance, the operator places the numeral or other indicia indicated by the graduations 26 and 27 onto the face of the wheel in a permanent fashion. For example, in the illustrated embodiment it is assumed that the assembly came into balance with the numerals 3 in alignment with the line 33 and, therefore, as shown in Fig. 4 the numeral 3 is applied to the face of the wheel. This completes the balancing operation, and at this point the spindle 33 is removed from the wheel and the attachment, and the assembly is mounted on the arbor 9 with the numerals 3 of the two plates in alignment with each other and with the line 33, as a result of which the wheel, when assembled in working position on the arbor, is in balance.

It will be seen that when this operation is completed the wheel 8 may be removed from the arbor for use of a different wheel on the arbor and may subsequently be replaced and directly be brought into balance, since the numerals placed on the face of the wheel and the center line 33 enable the balancing attachment to be unerringly placed in the proper position to effect balancing of the wheel.

I claim.

1. An attachment for balancing an abrasive wheel comprising disks of generally circular outline arranged in face to face relation, each having a central opening for the reception of an arbor carrying an abrasive wheel, each of said disks having a portion of the metal thereof removed along one radius of the disk to produce unbalance along a diameter coinciding with said radius, at least one of said disks being dished to provide a peripheral coplanar face on one side of the disk for engagement with the wheel and to space the central portion of the disk from the wheel, graduations along the periphery of each disk extending from directly opposite the aforesaid radius through ninety degrees, the graduations being identified by indicia progressing in opposite directions, and means for supporting the disks for rotary adjustment with respect to each other about the axis of the central opening.

2. The combination recited in claim 1 wherein the disks have holes disposed inwardly from the periphery of the disks arranged to provide equal unbalance to the disks.

3. The combination of claim 2, wherein the holes in the respective disks are equal in size and are equally spaced from the axis of the central opening.

4. The attachment of claim 1, wherein said disks are of sheet metal and said one dished disk is larger in size than the other disk and has an exposed annular marginal area when the disks are arranged in face to face relation.

SWAN F. ANDERSON.
